CIGARETTE BOX

Thaddeus Stepek, Rockville, Md., assignor to Sidney A. Alpert, Washington, D.C.

Filed Apr. 27, 1964, Ser. No. 79,707

Term of patent 14 years

(Cl. D85—2)

The figure is a perspective view of the cigarette box showing my new design.

The side and end not shown are substantially similar to the side and end shown, and the bottom is flat and unornamented.

I claim:

The ornamental design for a cigarette box, as shown and described.
